CORNELIUS WALSH, JAMES F. CONNELLY, AND ALFRED BRATT, OF NEWARK, NEW JERSEY, ASSIGNEES TO CORNELIUS WALSH.

Letters Patent No. 98,212, dated December 21, 1869.

IMPROVED HASP-LOCK.

The Schedule referred to in these Letters Patent and making part of the same.

We, CORNELIUS WALSH, JAMES F. CONNELLY, and ALFRED BRATT, all of Newark, in the county of Essex, and State of New Jersey, have invented a new and Improved Trunk-Hasp and Lock combined, which we describe as follows:

Nature and Objects of the Invention.

The hasp may be attached to the trunk-lid in customary manner, and may or may not, as preferred, be provided with a hinge and with a spring for throwing up the hasp when released. The lower part of our hasp fits within a case of peculiar construction, attached to the body of the trunk.

The lock is contained within the hasp, and has one, two, or more bolts, which, projecting in any one or more directions, engage within the case, so as to hold the hasp and case securely together.

When unlocked, the hasp may slide vertically into and out of the case, (which may dispense with the necessity of a spring, or even of a hinge,) or the hinged hasp may be withdrawn from the case in the usual way.

The cutting away of the trunk, which is necessary with trunk-locks now in use, to make room for the lock, projecting backward from the plate, weakens the trunk, and adds much to the cost of fitting.

We entirely dispense with such cutting away, by constructing our hasp, lock, and case without any backward projection from the plate or lock-case.

In packing trunks for shipment, both the trunk and the lock are often damaged from the projection of the latter. This danger is entirely avoided by the compact construction and flat form of our lock and its case.

General Description with Reference to the Drawings.

In the accompanying drawings—

Figure 1 is a front view of the hasp, lock, and lock-case or plate in position, with the cap of the lock removed.

Figure 2 is a front view of the lock, with the yoke omitted and the bolts retracted.

Figure 3 represents a vertical section of the hasp, lock, and case, in the plane indicated by the line x x , figs. 1 and 2.

Similar letters of reference indicate corresponding parts in both views.

The hasp here represented is made in two parts, a b , hinged together and provided with a spring, g , according to the invention of CORNELIUS WALSH, for which he has applied for Letters Patent.

Any such spring to throw up the hasp, and the hinge itself, may, if preferred, be dispensed with in connection with our invention.

The lock, which is applied to the lever end of the

hasp, may be constructed, as in the present illustration, with one, two, or more bolts, C C , pivoted to studs c c , and operated through the medium of a yoke-plate, D , which is actuated by a suitable key, works in a rectilinear path on guides d d . i , and engages with studs c^1 , on arms projecting from the backs of the bolts C .

c^1 c^2 are the holding-bits, which project from both sides of the lock when in their locked condition.

Bolts projecting from the bottom of the lock may be used in addition to, or instead of the side-bolts C , and any or all of them may be of hook-form, so as, by an outward and forward movement, to engage with the case.

I is a tumbler, pivoted to the stud i , and engaging in one of the notches d^1 or d^2 , in the yoke-plate D , to hold the latter in the position into which it is thrown by the key in locking and unlocking.

The spring J , bearing against the heel of the tumbler, presses and holds it into its position against the proper notch d^1 or d^2 of the yoke-plate, when it is released by the key.

The case within which the hasp-lock fits may be made in one, two, or more pieces. In the present illustration it is constituted of one casting, H , formed to fit the hasp, and with recesses h h , in proper positions to receive the bolts C .

The recess which receives the hasp is covered at back by a flat plate, H' , which may be riveted to the cast-shell H .

The hasp is recessed for the reception of the lock-works, and adapted to receive said recess by forward (if any) enlargement, instead of a backward projection being employed for the purpose, as heretofore. The back of the case or socket is thus enabled to be flush with the surface to which applied, and any "cutting away" for its reception avoided. The employment of a rigid hasp, sliding edgewise into its case or socket, as proposed, is also thus facilitated.

Operation.

The parts being in the position shown in fig. 1, the key is introduced and turned from left to right, as usual, for unlocking.

The first effect is to press the tumbler out of the notch d^1 , and the key then engaging in the notch d^2 of the yoke-plate, draws it straight downward, which, by depressing the inner ends of the pivoted bolts C C , withdraws them completely within the lock, and, at the same time, the tumbler I being released by the key, springs into the notch d^2 , so as to hold the yoke-plate in its depressed position.

It will be apparent that no leverage can be exerted against the projecting bits c^1 c^2 of the bolts, and hence they sustain but little strain, their office being only

to prevent the lock from sliding out of the case within which it is fitted in close contact. The projecting bits are supported by the walls at the precise points where the pressure is sustained by them, and therefore do not require to be large or heavy in order to bear any possible strain.

Claim.

We claim, as new—
The hasp, containing the lock-works, and the case

or socket for the reception and retention of the hasp, adapted to slide edgewise, one within the other, for engagement, as herein represented and described.

CORNELIUS WALSH.
JAMES F. CONNELLY.
ALFRED BRATT.
